DRAFT RIGGING KEY

Walter A. Byrd, Vicksburg, Miss., assignor of one-half to James D. Thames, Vicksburg, Miss.

Application July 16, 1948, Serial No. 39,144

2 Claims. (Cl. 85—3)

1

This invention relates to an improved draft rigging for railway cars and more particularly to a novel cross-key for such rigging.

Heretofore, it has been usual practice to lock the keys of draw bars in position each by a simple pin inserted transversely through the forward end of the key and, in turn, secured against displacement by a conventional cotter key. However, experience has proven that the cotter key becomes worn, rusted, or for other reasons, not infrequently displaced, with the result that the pin likewise becomes displaced to free the draw bar key, often with disastrous results.

An object of the present invention, therefore, is to provide a draw bar key having a novel latch which, when released, will gravitate to active position at a right angle to the key locking the key against retraction, wherein means will be provided for locking the latch in active position, and also wherein means will be provided for normally securing the latch in inactive position aligned with the key so that the key may be readily inserted through the usual aligned slots provided to receive the key.

A further object of the invention is to provide a key embodying means to alleviate sticking or freezing, as the latter is popularly called, of the key in the slots of the draft rigging, wherein said means will provide, after the key is installed, combined air ducts and drainage channels to afford ventilation as well as the release of moisture from between the parts, wherein said channels will, before the key is installed, serve to receive tie wires securing the latch in inactive position, and wherein, after the key is installed and it is desired to remove the key, said channels will also serve to receive a U-shaped clip which may be temporarily applied to secure the latch in inactive position so that the key may be withdrawn.

And the invention seeks, as a still further object, to provide means whereby the key, assuming it to be stuck or frozen in place, may be retractively started or, in other words, initially loosened, so that the key may be subsequently withdrawn without difficulty.

Other and incidental objects will appear during the course of the following description of the invention, and in the drawings:

Figure 1 is a plan view of a portion of a draft rigging showing, at the left, an installed key before the latch thereof is released and, at the right, an installed key having the latch thereof released.

Figure 2 is an edge elevation showing the latches of both keys in active position.

2

Figure 3 is a section on the line 3—3 of Figure 1.

Figure 4 is a section like Figure 3 but taken at one of the tie wires for the latch of the key. Figure 5 is a section on the line 5—5 of Figure 1.

Figure 6 is a perspective view of a typical key. Figure 7 is a perspective view of a clip provided to facilitate the removal of the key.

The structural details of any particular draft rigging are not of special import to the present invention, as such details vary widely, but all, in so far as I am aware, employ cross-keys for securing the draft bar in position. I have, therefore, shown as typical, only a pair of channeled side bars 10 which slidably receive a draft bar 11 provided at its forward end with a conventional coupler 12. As will be understood, the foregoing structure may, in actual practice, appear in sundry physical embodiments, differing in aspect as well as detail. As is usual, the side bars 10 and draft bar 11 are provided with slots 13 which may be aligned to receive draft keys, now to be described.

Removably inserted through the aligned slots 13 are draft keys, each indicated as a whole at 14, two being shown. However, the exact number of keys employed is immaterial, and I do not wish to be limited in this respect. As for the predominate features of said keys, each includes an oblong body 15, rectangular in cross section and having flat upper and lower parallel faces as well as flat parallel side edges. Formed on the body 15 at its rear end is a preferably circular head 16, but however, the exact shape of the head may be varied.

Considering now a single key 14 in detail, it will be noted, as particularly shown in Figure 6 of the drawings, that the body 15 thereof is formed near its forward end with transverse notches 17 located near the inner ends of a pair of confronting jaws 18. These jaws are provided with wedge-shaped heads 19 having inwardly converging beveled inner edges 20. Defining the jaws 18 is a longitudinal slot 21 medially of the body, which slot extends rearwardly from the notches 17.

Journaled upon the body 15 of the key is a latch 22 having an oblong body adapted to freely fit in the slot 21 and provided at its forward end with a dove-tailed head 23 normally received freely between the inclined edges 20 of the heads 19 of the jaws 18. Thus, when in inactive position, the latch 22 lies within the lines of the body 15 of the key flush therewith. However, the head 23 weights the latch at its forward end so that said latch will normally swing by gravity to active

position extending at a right angle to the body of the key.

Formed on or otherwise secured to the body of the latch at its side edges are sleeve trunnions 24 aligning with a transverse opening through the body. These sleeve trunnions are freely received in the notches 17, and extending through said trunnions as well as through the body of the latch is a pivot pin 25 fixed in the jaws 18 at the ends of said notches. The trunnions 24 provide an additional length of bearing for the latch 22 over and above the thickness of the body of the latch itself, and also provide stops adapted to coact with the jaws 18 for limiting the latch against forward displacement should either end portion of the pin 25 become sheared. As will be perceived, the latch with its trunnions may be readily installed from either side face of the body of the key.

Formed in the upper and lower faces of the body 15 of the key are spaced parallel channels 26 opening through the head 16. Like matching channels 27 are formed in the upper and lower faces of the latch 22. All of said channels may be of any approved depth and width.

The channels 26 are provided primarily as ducts adapted to permit a flow of air between the body 15 of the key and the side bars 10 and draw bar 11 tending to ventilate the contacting surfaces thereof and retard sticking or freezing of the key. Also, these channels, primarily, will further provide for drainage of moisture from between the parts.

Mounted upon the head 16 of the key are diametrically spaced jack screws 28 which may or may not, optionally, be a part of the permanent installation of the key. In any event, the threaded openings for the screws will be present in the head so that, assuming the screws to be installed, said screws may be turned to coact with the adjacent side bar 10 for starting the retraction of the key somewhat and breaking the seal-sticking of the key, after which the key may be removed in the usual manner.

In the present instance, the channels 26 and 27 are further employed as a means facilitating the securing of the latch 22 in inactive position flush with the body 15 of the key. To this end, tie wires 29 are employed. These wires are inserted through the head 16 to lie in the channels 26 and 27 and embrace the latch 22, being twisted together at their ends at the outer side of the head. The tie wires will thus lie flush with the body and latch at opposite sides thereof so that the key may be readily inserted through the matching slots 13 of the draft rigging, after which the tie wires may be cut and removed to permit the latch 22 to swing downwardly to active position.

To facilitate the removal of the key, I further provide a U-shaped clip 30, shown in detail in Figure 7 of the drawings. This clip may be formed of wire or other suitable material and is of a size to fit the body 15 of the key lying within an upper and lower pair of the channels 26 and matching channels 27. Thus, after the latch 22 has been swung to inactive position, the clip may be applied for holding the latch inactive, so that the key may be withdrawn.

In view of the foregoing, only a little further description seems necessary. The keys 14 with the tie wires 29 thereon are initially inserted through the slots 13, after which the wires are removed, when the latches 22 will automatically swing to active position, as shown in Figure 2, blocking displacement of the keys. Formed

through the heads 23 of said latches are transverse openings adapted to removably receive suitable keys 31 disposed to engage the heads 19 of the jaws 18 for limiting the latches against accidental movement to inactive position.

Having thus described my invention, I claim:

1. A key for draft rigging including an oblong rectangular body having flat side faces and provided at one end with a head and at its opposite end with a medial longitudinal slot opening through the side faces of the body and defining at opposite sides of said slot a pair of confronting jaws, a latch freely received in said slot and pivoted between said jaws, said latch being weighted to normally gravitate to active position extending at an angle to the body, aligned trunnions rigidly fixed to the latch and extending laterally from the side edges of the latch, a pivot pin extending through said jaws, latch and trunnions pivotally mounting the latch and normally alone sustaining all of the forward and rear thrust on the latch when the key is in use, and shoulders carried by the jaws to confront said trunnions and spaced apart to freely receive and accommodate the trunnions therebetween as well as permit the latch to be bodily installed in said slot from either side face of the body, said shoulders being normally out of contact with the trunnions to prevent sticking of the trunnions against said shoulders but closely confronting said trunnions to provide pairs of forward and rear emergency stops disposed for selective engagement by said trunnions when displaced by shearing of said pin and adapted to limit said displacement.

2. A key for draft rigging including an oblong rectangular body having flat side faces and provided at one end with a head and at its opposite end with a medial longitudinal slot opening through the side faces of the body and defining at opposite sides of said slot a pair of confronting jaws, a latch freely received in said slot and pivoted between said jaws, said latch being weighted at its forward end to normally gravitate to active position extending at an angle to the body, aligned trunnions integral with the latch and extending laterally from the side edges of the latch, and a pivot pin extending through said jaws, latch and trunnions pivotally mounting the latch and normally alone sustaining all of the forward and rear thrust on the latch when the key is in use, said jaws being formed at their inner edges with notches freely accommodating said trunnions and opening into said slot as well as through the side faces of the body to permit the latch to be bodily installed in said slot from either side face of the body, the side walls of said notches providing shoulders normally out of contact with said trunnions to prevent sticking of the trunnions against said shoulders but closely confronting said trunnions to provide pairs of forward and rear emergency stops disposed for selective engagement by said trunnions when displaced by shearing of said pin and adapted to limit said displacement.
